UNITED STATES PATENT OFFICE.

SALVADOR DOMINGUEZ, OF SAN ANTONIO, TEXAS.

POWER-MULTIPLYING MECHANISM.

1,199,164.

Specification of Letters Patent. Patented Sept. 26, 1916.

Application filed April 21, 1916. Serial No. 92,714.

To all whom it may concern:

Be it known that I, SALVADOR DOMINGUEZ, a citizen of Mexico, residing at San Antonio, in the county of Bexar and State of Texas, have invented a new and useful Power-Multiplying Mechanism, of which the following is a specification.

The object of the invention is to provide a comparatively simple mechanism for multiplying the efficient power of a prime mover of any of the well known types adapted to use as a motive agent steam, gas, electricity, etc., and designed to conserve and utilize kinetic energy and apply momentum with the utmost economy in order to attain the result sought.

With these and other objects in view, which will be developed in the course of the following description, the invention consists in a certain construction, combination and relation of parts hereinafter specifically set forth and it will be understood that changes in the form, proportions and minor details of construction may be resorted to within the scope of the claims, without departing from the spirit of the invention.

In the drawings illustrating one embodiment of the invention—Figure 1 is a side view or elevation of the power multiplying mechanism. Fig. 2 is a plan view of the same. Fig. 3 is a vertical sectional view on the line 3—3 of Fig. 1. Fig. 4 is a vertical sectional view on the line 4—4 of Fig. 2. Fig. 5 is a detail side view of one of the rocker actuators.

The mechanism embodies essentially a motor actuated by a prime mover, a stator embodying a base or support and co-operating with the motor, and transmission mechanism by which the power is conveyed to the driven element, from which it may be taken to perform the desired work.

In the illustrated embodiment of the invention the motor which in this instance consists of a shuttle or reciprocatory member embodies a frame having terminal trucks suitably connected as by bars 11 and having bearing wheels 12, which may be of the flanged type as shown to traverse tracks 13 supported by the base, said bearing wheels being secured to spindles 14 operating in

bearing boxes 15 at the opposite sides of each truck. The motor also includes a prime mover 16 which may be of any of the well known types and is shown as being carried by the connecting bars 11 between the trucks, in common with weights 17 which may be suitably arranged thereon to secure the maximum efficiency in obtaining the desired traction and operating effect, as will appear hereinafter. Secured to the spindles 14 or to the bearing wheels 12 are driving gears 18, traversing and coöperating with racks 19, also permanently secured to and supported by the base or stator, whereby as the motor frame is reciprocated, said gears in traversing the racks impart rotary movement to the spindles. Driving wheels are also mounted upon the trucks, two for each truck being illustrated in the drawings and being indicated at 20, each driving wheel having a sleeve shaft 21 fitted upon the spindle 14 and carrying a pulley 22 which is connected by a belt or similar means 23 to a driving pulley 24 of the prime mover, the belts running to one truck being crossed so as to impart to the driving wheels at opposite ends of the motor motion in opposite directions, that is, from the top downward toward the prime mover. These driving wheels contact peripherally with traction surfaces 25 also secured permanently in the base or stator and consisting in the construction illustrated of horizontal bars which are preferably superficially corrugated or roughened to insure the proper advance of the motor in one direction or the other by the contact of said driving wheels with the traction surfaces.

It will be noted that with the construction as so far described, the operation of the driving wheels is continuous, the set at one end of the motor turning in the opposite direction from the set at the other end, and these driving wheels or sets of driving wheels are designed to contact with their respective traction surfaces alternately. To accomplish this, one half of the periphery of each driving wheel is reduced or cut away, so that throughout one half of the periphery of the wheel the latter is radially reduced as shown at 26. When

the driving wheels of one truck are in contact with their traction surfaces, the driving wheels of the other truck are out of contact, and as the reduced portions of the sets of driving wheels face in the same direction, the truck frame by the operation of the driving wheels will be moved in one direction to the limit of its path and then the motion of the frame will be reversed by the action of the driving wheels of the other truck. It will be observed that the gears 18 with their bearing rollers or wheels are mounted as hereinbefore described to turn independently of the driving wheels.

In order to guard against injury to the base or stationary portion of the mechanism, and at the same time to utilize the rebound and momentum incident thereto, the trucks are provided at their outer extremities with buffer plates or members 27 supported by suitable buffer springs 28 held in place by rods 29, and the ends of the base or stationary frame are provided with corresponding buffer plates 30 yieldingly held in their normal positions by springs 31 and suitable rods 32.

A driven shaft 33 is suitably mounted in the stationary frame to actuate a belt pulley 34 or any other suitable driven member, and associated with this driven shaft it has been found expedient to employ main and auxiliary fly wheels 35 and 36 either or both of which may be thrown into engagement with the shaft, clutches 37, independently operable by levers 38 and 39 being employed for this purpose. In starting the engine it is desirable to throw in the auxiliary fly wheel and afterward the main wheel may be coupled, and in stopping the reverse procedure should be followed, after which the prime mover may be stopped.

Having now described the motor and the means by which it is caused to reciprocate regularly throughout the length of the tracks or bearings provided for it, reference is made to the transmission mechanism by which motion is communicated from the motor to the driven shaft or element and which consists essentially of a rocker having a suitable spindle 41 mounted in bearing boxes 42 and rocker actuators 43 which co-operate with shoes 44 on the rocker, said rocker actuators being carried by the spindles 14 and hence receiving motion from the gears 18 as they traverse the racks 19. Inasmuch as the rocker has an oscillatory movement while the path of the gear and of the motor frame is rectilinear, the bearing face of the shoe 44 and the contacting face of the rocker actuator have been developed upon kinematic lines, the latter being spiral as shown in detail in Fig. 5, and the former being an approximation to an ogee curve. These relative forms have been found effec-

tive largely for the reason that as the motor 65 advances from the position shown in Fig. 2, the rocker actuator at the forward end of the truck frame will contact gradually with the surface of the shoe on the rocker and will avoid unnecessary friction. During 70 this movement of the parts, the driving wheels at the rear of the motor frame are in contact with their traction surfaces, while the driving wheels at the forward end of the frame are out of contact with their traction surfaces. Obviously this order is 75 reversed when the motor frame has reached the limit of its movement in the direction indicated and whereupon the direction of movement is reversed to cause a reverse tilt- 80 ing movement of the rocker.

Carried by the driven shaft 33 are gears 45, one or more of which may be used, and meshing therewith are gears 46, which stand continuously in a common direction and 85 therefore impart a continuous rotary motion to the gears 45 and hence to the driven shaft. Such motion is communicated thereto through the crank shafts 47, which in turn are connected with the rocker 40, through 90 the medium of the levers 48 and the pitmen 49 and 50, both of which are adjustable as to length by means of turnbuckles or other equivalents.

From the foregoing description it will be 95 understood that the motor consisting of the reciprocating frame receives its motion from the prime mover, the energy of which is communicated through the belts and pulleys to the driving wheels located at opposite 100 ends of the motor frame and constructed and mounted to operate alternately, and that during these movements in opposite directions the gears 18 traversing the racks 19 serve to actuate the rocker actuators which 105 alternately act upon the shoes of the rocker to cause an oscillatory movement thereof, and the movement of the latter is communicated through suitable connections to the driven shaft to cause a continuous motion in 110 one direction thereof.

What is claimed is:—

1. A power multiplying mechanism having a stator, a motor having traction wheels operated by a prime mover to traverse the 115 stator, a driven element, and transmission mechanism actuated by the motor and connected with the driven member.

2. A power multiplying mechanism having a stator, a motor having a reciprocating 120 member provided with traction wheels actuated by a prime mover and traversing said stator, a driven element, and transmission mechanism actuated by the reciprocating member and connected with the driven member. 125

3. A power multiplying mechanism having a stator including traction surfaces, a

motor actuated by a prime mover and having driving wheels traversing said traction surfaces and actuated by the prime mover, a driven element, and transmission mechanism actuated by the motor and connected with the driven member.

4. A power multiplying mechanism having a stator including traction surfaces, a motor having a prime mover and provided with driving wheels actuated thereby and traversing said traction surfaces, a driven element, and transmission mechanism connected with the driven member and including an oscillatory element and means carried by the motor for oscillating the same.

5. A power multiplying mechanism including a stator having a plurality of traction surfaces, a motor including a prime mover and having a reciprocatory member guided by the stator, said motor also including driving wheels for respectively traversing said traction surfaces and being actuated by the prime mover, said driving wheels being adapted for alternate engagement with said traction surfaces and being at different points of different radial dimensions, a driven element, and transmission mechanism actuated by the reciprocatory member of the motor and connected with the driven member.

6. A power multiplying mechanism having a stator, a motor coöperating with the stator, carrying a prime mover and having a reciprocatory member traversing the stator, cushioning means at the limits of movement of said reciprocatory member, a driven element, and transmission mechanism actuated by said reciprocatory member and connected with the driven member.

40 7. A power multiplying mechanism having a stator, a motor including a prime mover and having a reciprocatory member and means for communicating motion thereto, a rocker, a driven element and means for transmitting motion from said rocker to the driven element, and a rocker actuator carried by the reciprocatory member of the motor for imparting oscillatory movement to the rocker.

50 8. A power multiplying mechanism having a stator, a motor including a prime mover and mounted upon said stator, said motor having means for imparting reciprocatory movement to said member, a driven element, a rocker connected operatively with said driven member, and a rocker actuator carried by the reciprocatory member of the motor, said rocker and rocker actuator having contacting faces developed upon kinematic lines.

60 9. A power multiplying mechanism having a stator, a motor having a reciprocatory member guided by and mounted upon said stator, said motor including a

prime mover, and driving wheels actuated by said prime mover and coöperating with the stator, a driven element, a rocker connected with said driven element for imparting motion thereto, and a rocker actuator for imparting motion to said rocker, said rocker having a shoe provided with a contact face arranged on an ogee curve, and said rocker actuator having a spiral contacting face for coöperation therewith.

10. A power multiplying mechanism having a motor including a prime mover, a driven member, and power transmission mechanism including a rocker having shoes on opposite sides of the fulcrum, rotary rocker actuators for contact with said shoes, and connections between the rocker and driven member, said rocker actuators being carried by a reciprocatory element of the motor.

11. A power multiplying mechanism having a motor including a prime mover, traction means actuated by the prime mover, and a reciprocatory element actuated by the traction means, a driven member, and transmission mechanism including a rocker having terminal shoes, rocker actuators carried by said reciprocatory member of the motor, and connections between the rocker and said driven member, said rocker shoes and rocker actuators having kinematically developed contacting faces, said rocker actuators being rotary and having actuating means consisting of gears traversing stationary racks during the movement of the reciprocatory member of the motor.

100 12. A power multiplying mechanism having a stator, a motor carrying a prime mover and having a reciprocatory member rectilinearly guided upon the stator, said motor also having driving wheels, and the stator having traction surfaces for engagement by said wheels, a driven member, and transmission mechanism including a rocker having shoes, rotary rocker actuators having faces to traverse said shoes, intermeshing gears and racks for imparting rotary motion to said rocker actuators, a gear connected with said driven member, other gears meshing respectively with said first named gear, and connections between said rocker and said second named gears including crank shafts, rocking levers, and pitmen respectively connecting opposite ends of said rocking levers with the crank shafts and the rocker.

120 13. A power multiplying mechanism having a base, a driven member mounted therein, main and auxiliary fly wheels mounted upon said driven member, independently operable clutch devices for connecting said fly wheels with the driven shaft, a motor including a prime mover, a reciprocatory member, and traction devices including drive

wheels connected with said prime mover and coöperating with traction surfaces on the base, a rocker operatively connected with the driven shaft, and means carried by the 5 reciprocating member of the motor for alternately pressing the opposite extremities of said rocker.

In testimony that I claim the foregoing as my own, I have hereto affixed my signature in the presence of two witnesses.
